United States Patent Office

Des. 209,870
Patented Jan. 9, 1968

209,870

PAIL OR THE LIKE

George Yates, Jr., Los Angeles, Calif.
(151 Cumberland Road, Glendale, Calif. 91202)

Filed Mar. 20, 1967, Ser. No. 6,305

Term of patent 14 years

(Cl. D58—17)

I claim:

The ornamental design for a pail or the like, as shown.
